LADDER WEB

Schuyler J. Taylor, Portland, Conn., assignor to
The Russell Manufacturing Company, Middle-
town, Conn., a corporation of Connecticut

Application September 16, 1940, Serial No. 356,971

9 Claims. (Cl. 66—170)

This invention relates to improvements in ladder-web which is primarily employed for supporting the slats of Venetian blinds or the like.

One object of this invention is to provide an improved ladder-web of lower cost.

Another object of this invention is to provide an improved ladder-web which will permit the slats of the Venetian blinds to come closer together when the Venetian blind is raised to its highest position.

Another object of the invention is to permit the passage through the slats of the blind when opened of an increased amount of air and light.

A further object is to produce a tape which collects less dust, and shows stains and discolorations to a less degree than the usual flat wide tape.

With the above and other objects in view, as will appear to those skilled in the art from the present disclosure, this invention includes all features in the said disclosure which are novel over the prior art.

In the accompanying drawings forming part of the present disclosure, in which certain ways of carrying out the invention are shown for illustrative purposes:

Fig. 1 is a perspective view of a fragmental portion of a Venetian blind employing ladder-web made in accordance with the present invention;

Fig. 2 is a front elevation of the construction shown in Fig. 1;

Fig. 3 is a front elevation similar to Fig. 2 with the slats of the Venetian blind in partially closed position;

Fig. 4 is a horizontal-sectional view on line 4—4 of Fig. 2;

Fig. 5 is an enlarged fragmental perspective view of a portion of a Venetian blind employing ladder-web made in accordance with the present invention, with the knitted construction shown in opened-up or loosened condition for clearness;

Fig. 6 is a perspective view similar to Fig. 5 of a modified form of ladder-web, but omitting the blind slats and raising rope;

Fig. 7 is a perspective view similar to Fig. 6 of still another modified form of ladder-web made in accordance with the present invention; and

Fig. 8 is a fragmental perspective view similar to the lower left-hand portion of Fig. 7, showing the use of two strands constituting the member which is knitted to form a cord-like main web.

In the description and claims, the various parts and steps are identified by specific names for convenience but they are intended to be as generic

in their application as the prior art will permit.

Referring to the particular form of the invention illustrated in Figs. 1 to 5 of the drawings, the ladder-web generally designated by the numeral 10 includes front and back or first and second vertical cord-like main webs 11 and 12 interconnected at suitable intervals by ladders 13 each formed of a pair of strands 14 and 15. Venetian-blind slats 16 rest upon the ladders 13 and each slat 16 has a usual slot 17. A raising rope 18 extends between the ladder-strands 14 and 15 and through the slots 17 in a well-known manner. Or, the raising rope could pass first on one side and then on the other side of both strands 14 and 15 at successive slats. If desired, one of the strands 14, 15 of each pair of ladder strands could extend along the top of a blind slat while the other one is underneath in supporting position. Although only one ladder web and one end of each blind slat is shown, it will be understood that the usual operative construction employs two ladder-webs, one at each end of the blind slats.

As is clearly illustrated in Fig. 5, the vertical or main webs 11 and 12 are respectively mainly formed of knitted strands 19 and 20. By referring to the lower left-hand portion of Fig. 5 it will be seen that the ladder-strand 14 travels upwardly in interlaced relation with the knitted strand 19 and then extends across transversely beneath the lowest slat 16 and then joins in, in interlaced relation, with the knitted strand 20 of the main web 12 extending upward until it reaches a proper position for the second slat 16, whereupon it extends across as one of the ladder-strands supporting the second slat 16, and then again becomes interlaced with the knitted strand 19 of the main web 11 and extends upwardly in interlaced relation therewith until it reaches proper position to extend across again as part of the next ladder support 13 for the next blind slat 16.

Similarly, by referring to the lower right-hand corner of Fig. 5 it will be seen that the other ladder-strand 15 extends upward in interlaced relation with the knitted strand 20 of the main web 12 until it reaches a proper position whereupon it extends across as one of the ladder-strands of the ladder 13 supporting one end of the lower slat 16, and then extends upward in interlaced relation with the knitted strand 19 of the main web 11 until it reaches a proper position, whereupon it crosses as one of the ladder-strands and extends upwardly in interlaced relation with the knitted strand 20 of the main web

12 until it reaches the proper ladder position for the next slat 16.

In the modified form of the invention illustrated in Fig. 6, the ladder-web 10a includes the first and second or front and rear main webs 11a and 12a with ladders 13a. The main webs 11a and 12a are respectively formed of knitted strands 19a and 20a with a ladder 13a interconnecting these main webs 11a and 12a. The essential difference between the construction illustrated in Fig. 6 from that illustrated in Fig. 5 resides in the fact that the ladder 13a of Fig. 6 differs from the ladder 13 of Fig. 5 in that the ladder 13a is formed of a single strand instead of two separate strands as in the case of the ladder 13 of Fig. 5. Thus the ladder 13a is formed by a single ladder-strand 21 which is interlaced with the knitted strands 20a of the main web 12a until it reaches a proper position for the first ladder whereupon it crosses over to the main web 11a and is anchored with the main web 11a and thereupon immediately returns to thus complete the formation of the lower ladder 13a formed of two ladder portions of the strand 21, as shown in Fig. 6. Thereupon the returning portion of the ladder strand 21 is again interlaced with the knitted strand 20a of the main web 12a as it travels upward until it reaches the position of the next ladder 13a whereupon it crosses over and is again anchored to the knitted strand 19a of the main web 11a and then again returns to the main web 12a to thus form the second ladder 13a, whereupon it is again interlaced with the knitted strand 20a of the main web 12a and travels upward preparatory to similarly forming another ladder 13a.

The modified construction illustrated in Fig. 7 is similar to that illustrated in Fig. 6, differing therefrom mainly in the mode of forming the ladders. Thus referring to Fig. 7 the ladder-web 10b includes the first and second main webs 11b and 12b, each respectively formed of a knitted strand 19b and 20b. Each ladder 13b is formed of a single strand 22. Thus referring to the lower right end of Fig. 7, the ladder-strand 22 extends upwardly in interlaced relation with the lower end portion of the knitted strand 20b of the main web 12b until it reaches proper position to form the first ladder 13b, whereupon it crosses over to the main web 11b whereupon it is interlaced with the knitted strand 19b of the main web 11b, and then extends upwardly in interlaced relation with the knitted strand 19b until it reaches the position to form the second ladder 13b whereupon it crosses over and then extends upwardly in interlaced relation with the knitted strand 20b of the main web 12b, and so on. In using this construction in a Venetian blind, the raising rope would pass first on one side and then on the other side of the ladder-strand 22 at successive slats.

In Figs. 5, 6 and 7 which illustrate the knitted construction in an opened-up or loosened condition for clearness, the portions of the ladder-strands which are interlaced or interwoven with the knitted strands are illustrated in a fairly straight condition, although in the actual knitted construction, the knitted loops will be fairly tight and the portions of ladder-strands interlaced therewith will bend more or less sharply back and forth as they extend through the knitted loops.

This invention contemplates forming each of the main webs of one or more knitted strands and interconnecting the main webs with one or more ladder-strands to form the ladders. Thus, for

example, in Fig. 8 the main web 11c is shown as formed by knitting two strands 19c. The entire ladder-web can be made of any suitable flexible strand material such, for example, as strands of cotton or other textile material, and can be knitted upon various knitting machines known to the art such, for example, as a knitting loom similar to the old knitting loom known as the Raschel Knitting Machine, or a knitting loom made by the New England Butt Company, of Providence, Rhode Island, or by the Cidega Corporation, of New York city, or by the Eppler Machine Company, of Philadelphia.

Ladder-web made in accordance with the present invention employs a minimum of textile material, can be rapidly manufactured at very low cost, presents a neat, attractive appearance, and when the Venetian blind is raised to its completely closed position, it results in the main or front and back knitted webs folding in a particular way that brings about two results. Thus, referring to Fig. 3 which is more or less diagrammatic for clearness, and therefore does not show the slats in their completely closed position because it would not be easy to illustrate the folded main webs clearly, it will be observed that the front web 11 is arranged in back-and-forth loops 23 in front of, and not between, the slats 16 with the general plane of the loops approximately parallel to the general plane of the adjacent or front edges of the slats 16. Thus it will be seen that there is nothing between the slats except the ladder-strands, with the result that the slats 16 can close very close together, and in their fully closed condition the folded loops 23 will actually slide past one another into overlapped relation to some extent, but will not change their general position as shown in Fig. 3. In a similar way, the rear main web will form loops, the general plane of which is approximately parallel to the general plane of the adjacent or rear edges of the slats 16, without getting between the slats. Thus it will be seen that the slats of a Venetian blind employing my improved ladder-web can be closed very tightly together with minimum waste of space between the slats when in completely closed position. Also, inasmuch as the main webs do not interpose themselves between the slats, and stick out beyond the edge of the slats both in front and rear of the slats, as is usual in the regular flat ladder-tape of commerce, my improved ladder-web does not rub against windows and thus become dirty on the edge portions which rub against the windows, as is true in the case of the usual wide flat-band ladder-tape when Venetian blinds employing it are set in the window frame and somewhat close to the window, as is frequently done.

Also, due to the small size of the main webs of my improved ladder-web, they permit the passage through the slats of the blind when opened, of an increased amount of air and light, and the main webs collect less dust, and show stains and discolorations to a less degree than the usual flat wide ladder tape.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A ladder-web for use with blind-slats to form a Venetian blind comprising: first and second cord-like main webs each mainly formed of one or more knitted strands; and ladders formed of strands interconnecting said cord-like main webs; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

2. A ladder-web for use with blind-slats to form a Venetian blind comprising: first and second cord-like main webs each mainly formed of one or more knitted strands; and one or more strands each extending along at least portions of at least one of said cord-like main webs and also forming ladders interconnecting said cord-like main webs; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

3. A ladder-web for use with blind-slats to form a Venetian blind comprising: first and second cord-like main webs each mainly formed of one or more knitted strands; and one or more strands each extending along and interlaced with at least portions of at least one of said cord-like main webs and also forming ladders interconnecting said cord-like main webs; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

4. A ladder-web for use with blind-slats to form a Venetian blind comprising: first and second cord-like main webs each mainly formed of one or more knitted strands; and first and second ladder-strands, the first ladder-strand extending along the first cord-like main web and the second ladder-strand extending along the second cord-like main web, of a length-section of the ladder-web, and then said ladder-strands extending oppositely to one another across between the cord-like main webs to form a ladder, and then the first ladder-strand extending along the second cord-like main web and the second ladder-strand extending along the first cord-like main web, of the next length-section of the ladder-web, and then said ladder-strands extending oppositely to one another across between the cord-like main webs to form another ladder; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

5. A ladder-web for use with blind-slats to form a Venetian blind comprising: first and second cord-like main webs each mainly formed of one or more knitted strands; and first and second ladder-strands, the first ladder-strand extending along and interlaced with the first cord-like main web and the second ladder-strand ex-

tending along and interlaced with the second cord-like main web, of a length-section of the ladder-web, and then said ladder-strands extending oppositely to one another across between the cord-like main webs to form a ladder, and then the first ladder-strand extending along and interlaced with the second cord-like main web and the second ladder-strand extending along and interlaced with the first cord-like main web, of the next length-section of the ladder-web, and then said ladder-strands extending oppositely to one another across between the cord-like main webs to form another ladder; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

6. A ladder-web for use with blind-slats to form a Venetian blind comprising: first and second cord-like main webs each mainly formed of one or more knitted strands; and a ladder-strand extending along the first cord-like main web of a length-section of the ladder-web, and then extending across and connecting with the second cord-like main web and then extending back to the first cord-like main web to form a ladder, and then extending along the first cord-like main web of the next length-section of ladder-web; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

7. A ladder-web for use with blind-slats to form a Venetian blind comprising: first and second cord-like main webs each mainly formed of one or more knitted strands; and a ladder-strand extending along and interlaced with the first cord-like main web of a length-section of the ladder-web, and then extending across and connecting with the second cord-like main web and then extending back to the first cord-like main web to form a ladder, and then extending along and interlaced with the first cord-like main web of the next length-section of ladder-web; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

8. A ladder-web for use with blind-slats to form a Venetian blind comprising: first and second cord-like main webs each mainly formed of one or more knitted strands; and a ladder-strand extending along the first cord-like main web of a length-section of the ladder-web, and then extending across between the cord-like main webs to form a ladder, and then extending along the second cord-like main web of another length-section of the ladder-web, and then extending across between the cord-like main webs to form another ladder; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

9. A ladder-web for use with blind-slats to form a Venetian blind comprising: first and second cord-like main webs each mainly formed of one or more knitted strands; and a ladder-strand extending along and interlaced with the first cord-like main web of a length-section of the ladder-web, and then extending across between the cord-like main webs to form a ladder, and then extending along and interlaced with the second core-like main web of another length-section of

10

the ladder-web, and then extending across between the cord-like main webs to form another ladder; and each said cord-like main web, when the blind-slats on which said ladder-web is used are closed together, being adapted to arrange itself in back-and-forth loops the general plane of which is approximately parallel to the general plane of the edges of the blind-slats which are adjacent to said cord-like main web.

SCHUYLER J. TAYLOR.
